(57) CLAIM

The ornamental design for a cap-form lamp shade with sports logo, as shown and described.

DESCRIPTION

FIG. 1 is a side elevational view showing the novel cap-form lamp shade with sports logo of the claimed design;
FIG. 2 is a front elevational view thereof;
FIG. 3 is a top plan view thereof; and,
FIG. 4 is a front, right-side perspective view thereof.
The cap-form lamp shade is translucent in order to highlight the sports logo.

The broken lines are shown in the views for illustrative purposes only and form no part of the claimed design.
